UNITED STATES PATENT OFFICE

148,766

DESIGN FOR A PERFUME DIFFUSER

Henry Cobbs, Little River, Fla.

Application February 11, 1947, Serial No. 136,851

Term of patent 14 years

(CL. D16—2)

To all whom it may concern:

Be it known that I, Henry Cobbs, a citizen of the United States of America, residing at Little River, in the county of Dade and State of Florida, have invented a new, original, and ornamental Design for a Perfume Diffuser, of which the following is a specification, reference being had to the accompanying drawing, forming part thereof.

The figure is a perspective view of a perfume diffuser, showing my new design.

The back of the perfume diffuser is substantially plain.

I claim:

The ornamental design for a perfume diffuser, as shown and described.

HENRY COBBS.
